UNITED STATES PATENT OFFICE.

ANDRU G. PAPPADAKIS, OF DETROIT, MICHIGAN.

ALARM MECHANISM.

Application filed December 3, 1925. Serial No. 73,023.

This invention relates to a new and improved alarm mechanism, particularly of the type used to sound an alarm through the rotation of the door knob connected with a door lock, and to combine therewith means for locking a latch thereof in either of its extreme positions.

It is the object of this invention, among other things, to provide a simple and effective mechanism of this character, wherein the alarm mechanism is so arranged and adjusted that it may be placed in either an operative or inoperative position, as desired; a further object being to provide mechanism that will hold the latch against movement in either its in or out position and that may be released from either side of the door to permit the latch to move back and forth as normally.

To these, and other ends, my invention consists in the alarm mechanism, having certain details of construction and combinations of parts as will be hereinafter described and more particularly pointed out in the claims.

Referring to the drawings, in which like numerals of reference designate like parts in the several figures;

Figure 1 is a plan view of a lock case with the cover removed showing its interior mechanism partly in section;

Figure 2 is an end view thereof, the parts in section being taken generally upon line 2-2 of Figure 1;

Figure 3 is an enlarged transverse sectional view of a portion of the lock and adjacent parts upon line 3-3 of Figure 1;

Figure 4 is an enlarged view of a fragmentary portion of a door, in which the lock is mounted, showing particularly the inside of the door and a portion of the mechanism for locking the latch;

Figure 5 is an enlarged plan view of the rear end of the lock and a portion of the locking mechanism.

The bell and the particular mechanism for striking the same is of the same general type as is shown in Letters Patent No. 1,515,788, issued to me November 18, 1924, and consists essentially of a bell 10 mounted upon a post 11, upon which is loosely mounted the hammer carrier, comprising the parallel plates 12 connected by pins 13, upon which are mounted the hammers 14 with a free axial and lateral movement.

Slidably mounted within the lock case 17 is the latch 18, which is operated in the usual

manner through a knob 19 upon the spindle 20. Upon this spindle is fixed the cam plate 21 having near the outer end thereof a cam slot 22, into which projects a pin 23 fixed in the sector 24 pivotally mounted upon the stud 25. The teeth 26 of this sector mesh into those of the pinion 27 rotatably mounted upon the post 11, and the teeth of which mesh into those of the pinion 28' with which is connected the pinion 28, the teeth of which mesh into those of the pinion 16.

Rotation of the knob 19 in either direction imparts a rotary movement to the hammer carrier about the post 11, through the cam plate 21, sector 24 and pinions 27 and 28. This movement throws the hammers 14 outwardly and by striking the bell 10 sound the alarm.

The spring 30 between the upper of the plates 12 and the inside of the bell maintains the lower of said plates against the disk 15 with sufficient pressure to enable the hammer carrier to acquire the rotary movement of the disk.

I provide with this mechanism new and novel means for disconnecting the pinions 16 and 28, whereby the former may rotate freely without imparting movement to the latter and thereby disengage the mechanism that operates the hammer carrier and render the alarm mechanism inoperative. Such means consists essentially of two slides 31 and 32, each of which has a head portion 33, which projects through openings 34 in the lock case 17. The inner ends of these slides are supported and move upon the lug 35 and have an operative connection with each other through the rock member 36, which is operatively connected with the lug 35 by the stud 37. This rock member has an opening at one end to receive a stud 38 in the slide 31 and provided with a slot 39 at its opposite end, into which projects the stud 40 in the slide 32. The inner end 41 of the slide 32 is at an angle to the axis of the head portions 33, the outer face of which rides upon a similarly inclined cam face upon the lug 35 (Figure 2) and terminates at its outer end in the yoke 42, which straddles the pinion 16 and lies under the disk 15.

In the position of the parts as shown in Figures 1 and 2, the pinions 16 and 28 are in mesh with each other, but when the slide 32 is pushed inwardly the yoke 42 thereon moves upwardly parallel with the axis of the post 11, engages the underside

of the disk 15 and lifts it and the pinion 16 above and out of engagement with the pinion 28, thus separating these pinions, and while the parts are in these relative positions 5 the hammer carrier will not rotate.

Between the slides 31 and 32 is a spring 43, which is fixed to the slide 31 and is provided with a detent 44 that projects into either one of the two notches 45 and 46, so 10 as to hold the slide 32 against accidental movement in its in and out positions.

As the latch 18 and the head portions 33 of the slides 31 and 32 project through the same face of the case, obviously the alarm 15 mechanism cannot be disconnected so as to silence the alarm when the door is closed and said face is inaccessible.

The numeral 47 indicates a latch of the usual construction, with which is connected 20 two rods 48, which project through the cross head 49 held against movement in one direction by the lugs 50 connected with the cap 54. On the inner end of each of the rods 48 are the head plates 51, between which is 25 an open space 52. Surrounding each of the rods 48 is a spring 53, which exerts its tension so as to move the latch 47 to its out position. The latch 47 is moved to its in position by the rotation of the button 55, 30 upon the shank 56 of which is the hub 57, the ears 58 of which engage the face of each of the head plates 51.

Movably mounted within the button 55 is a plunger 59, the inner end 60 of which is 35 reduced in diameter and is surrounded by a spring 61, which exerts its tension so as to move the plunger to its up position substantially as shown in Figure 3, wherein its outer end projects above the button 55. 40 Projecting radially from the plunger 59, through a slot 62 in the shank 56, is a stop pin 63, which during the rotation of the button 55 may move above or below the plane of the springs 64, shown herein as 45 three in number, and fixed and connected with the plate 65 secured to the cap 54 within a recess 66 in the door 67, which recess is covered by the plate 68 secured by screws 69, or the like.

50 During the rotation of the knob or button 55 to move the latch 47 to its in position and to its out position, the outer end of the stop pin 63 passes over the heads of the springs 64. If, however, it is desired to 55 lock the latch against movement in either direction, the plunger 59 is pressed inwardly, at which time the outer end of the stop pin 63 is passed under the head of the springs 64 and when this pressure is released 60 the spring 61 moves the plunger 59 outwardly, at which time the stop pin engages one of the springs 64 and is held 65 against further outward movement and its inner end is either in front or in rear of the head plates 51, as may be predetermined.

As the open space 52 is of less diameter than the plunger 59, it is impossible for the latch 47 to be moved when being held in its position, as shown by dotted lines in Figure 5, or its out position if the plunger is on the 70 upper side of the head plates 51.

I have shown three of the springs 64, the uppermost one in Figure 4 being used to hold the latch in its in position, the central 75 spring when the latch is in its outermost position and the lowermost when the latch is in its innermost position, and the inner end of the shank 59 with the latch parts substantially in the position shown by broken lines in Figure 5.

The knob button 55 is upon the inside of the door and the only parts exposed are this knob, all of the other parts being concealed under the plate 68.

From the outside of the door the plunger 85 59 is released from the pressure of the spring 64 through a key 70, which projects into a cylinder 71, between which and the plunger 59 is a link 72, the inner end of which projects into a recess in the inner end 90 of plunger 60, substantially as shown in Figure 5. This recess is of sufficient depth to permit the plunger 59 to slide therein between the extremes of its movement.

The open space 52 between the head plates 95 51 is of sufficient size to permit the latter to pass the link 72 during its movement.

Irrespective of whether in its open or closed positions, the latch may be released upon the retaining mechanism by the key 100 70 which rotates the plunger 59 and releases the stop pin 63 in contact with the spring 64.

Within the scope of the appended claims, the details of this mechanism may be modified without departing from the spirit of 105 my invention.

What I claim as new and desire to secure by Letters Patent is:—

1. In a device of the character described 110 having a case, a latch, means for actuating the latch; an alarm mechanism having an operative connection with and set in motion by the movement of the latch actuating means, and comprising a bell, a hammer to 115 strike the bell, and hammer actuating means; and a manually controlled slide for shifting the relative position of the parts of the hammer actuating means to disconnect them from each other and render the 120 alarm mechanism inoperative, said slide being exposed for operation through the same face of the case as the latch, whereby the alarm mechanism may be rendered inoperative only when the lock is in such position 125 as to expose said face.

2. In a device of the character described; a case having a part with a cam face thereon within the case, a latch, and means for actuating the latch; an alarm mechanism having 130

an operative connection with and set in motion by the movement of the latch actuating means, and comprising a bell, a hammer to strike the bell, and hammer actuating mechanism;

5 and means for disconnecting some of the parts of the hammer actuating mechanism, whereby the alarm mechanism is rendered inactive, comprising a plurality of slides actuated from the exterior of the case, 10 and the movement of one of which is controlled in part by said cam.

3. In a device of the character described; an alarm mechanism having a bell, a hammer to strike the bell, and hammer actuating means, comprising a gear and pinion; and a manually controlled reciprocating device for shifting the relative position of the gear or pinion, whereby they are disconnected from each other and the alarm mechanism 20 rendered inoperative, this device comprising a slide that is actuated from the exterior of the lock and having a yoke portion, which during the movement of the slide in one direction engages a part adjacent to the gear 25 or pinion and imparts axial movement thereto, and a second slide having an operative engagement with the first slide and by means of which the first slide is moved in a direction the reverse of that above mentioned.

4. In a device of the character described; an alarm mechanism having a bell, a hammer to strike the bell, and hammer actuating means, comprising a gear and pinion; and a manually controlled reciprocating device for shifting the relative position of the gear or pinion, whereby they are disconnected from each other and the alarm mechanism 35 rendered inoperative, this device comprising a slide that is actuated from the exterior of the lock and having a yoke portion which

during the inward movement of the slide travels in a path at substantially a right angle to the length thereof, and engages a part adjacent to the gear or pinion and imparts axial movement thereto, and a second slide having an operative engagement with the first slide and by means of which the latter is moved in an outward direction. 45

5. In a device of the character described; an alarm mechanism having a bell, a hammer to strike the bell, and hammer actuating means, comprising a gear and pinion; and a manually controlled reciprocating device for shifting the relative position of the gear 50 or pinion, whereby they are disconnected from each other and the alarm mechanism rendered inoperative, this device comprising a slide that is actuated from the exterior of the lock and having a yoke portion which during the movement of the slide in one direction engages a part adjacent to the gear or pinion and imparts axial movement thereto, a second slide, a rock member connecting both of these slides, and through which inward movement of the second slide imparts an outward movement to the first slide. 55

6. In a device of the character described, a case having a part with a cam face thereon within the case; an alarm mechanism having a bell, a hammer to strike the bell, and hammer actuating means, comprising in part a gear and pinion; and means as a manually controlled reciprocating device, one end of which during such reciprocation acquires a 70 substantially right angle movement from the said cam face and by reason thereof imparts axial movement to the pinion and renders the bell mechanism inactive. 75

In testimony whereof, I have hereunto affixed my signature.

ANDRU G. PAPPADAKIS.
